UNITED STATES PATENT OFFICE.

CHARLES MATTHEWS, JR., AND ERNEST E. LAUN, OF CHICAGO, ILLINOIS.

DEVICE FOR INTERMITTENT GAS-LIGHTS.

No. 830,092.

Specification of Letters Patent.

Patented Sept. 4, 1906.

Application filed February 8, 1905. Serial No. 244,770.

To all whom it may concern:

Be it known that we, CHARLES MATTHEWS, Jr., and ERNEST E. LAUN, citizens of the United States, residing at Chicago, county 5 of Cook, and State of Illinois, have invented certain new and useful Improvements in Intermittent Gas-Lighting Apparatus, of which the following is a full and complete specification, reference being had to the accompanying drawings.

Our invention relates to devices for intermittently supplying gas to a burner wherein the gas supplied to such burner is controlled by a valve that is connected with the moving 15 mechanism of an ordinary meter.

Broadly speaking, apparatus of this general character has been devised; but it is our object to devise by our invention more simple and efficient mechanism than has heretofore been employed; to provide an improved valve for automatically cutting off the supply of gas to the pipe or pipes carrying it to the place or places to be lighted; to provide an improved construction for keeping gas always 20 supplied to pilot-lights, from which the main burners are successively lighted as the valve rotates, and to improve generally the construction and operation of apparatus of this class.

That which we believe to be new will be pointed out in the claims.

In the drawings, Figure 1 is a vertical section. Fig. 2 is a horizontal section through the controlling-valve and its casing, the section being taken at line 1 1 of Fig. 1. Fig. 3 is a horizontal section at line 2 2 of Fig. 1. Fig. 4 is an enlarged detail showing the relative arrangement of one of the gas-burners and its pilot-light.

Referring to the several figures of the drawings, in which corresponding parts are indicated by the same reference-letters, A indicates a gas-meter of ordinary type, the side of the same being partly broken away to 45 illustrate some of the interior mechanism.

B indicates a sleeve arranged vertically in the construction shown and attached to the top of the gas-meter by a plate B², preferably formed integral with such sleeve, which is 50 bolted or otherwise firmly secured to such gas-meter. At the upper end of the sleeve B is another plate B³, which, like plate B², is preferably formed integral with the said sleeve.

B' indicates a vertically-disposed shaft 55 journaled in the sleeve B, to the lower end of which is secured a crank-arm C, suitably connected to another crank-arm C', with which the gas-meter A is equipped, as shown.

E indicates a casing fitting over and tightly 60 secured upon the plate B³, the plate B³ thus forming the lower wall of a chamber and the casing E the upper and side walls thereof. The chamber thus formed is indicated by E'.

F indicates a cylindrical valve connected 65 to the upper end of the vertical shaft B', so as to turn therewith. The under face of this valve F is provided with two relatively large recesses F' and F², located at opposite sides, as best shown in Fig. 2. The solid portion of 70 the valve between these recesses, as well as the edge portion of the valve, rests upon and fits closely to the upper face of the plate B³.

f indicates openings in the valve F, through which gas can pass from the chamber E' to said recesses F' and F².

As clearly shown in Fig. 2 and as indicated in dotted lines in Fig. 3, the solid portion of the valve intermediate of the recesses F' and F² is notched on its forward or leading edge, 80 considered with reference to the direction of movement of the valve, so as to form a series of projections f', that are adapted to successively close certain openings e in the bottom of the chamber E', through which and 85 through the pipes hereinafter described the gas is conducted to the places where it is to be consumed. The rear edge of the solid portion of the valve is notched or cut away to correspond to the projections on the forward 90 edge, so that the time that each opening in the bottom of the chamber is cut off or obstructed will be the same as any other of the said openings.

h indicates a series of pipes communicating 95 with holes e through the plate B³, which pipes are adapted to conduct gas to the point or points of combustion. In the construction shown these pipes h lead to different compartments of a sign H, where they each terminate in a gas-burner g'. As shown, each of the compartments of the sign H is provided with a letter g in its front face, the different letters being separated from each other by opaque division-walls H', so that 100 when a burner in any one compartment is lighted the light from such burner will be 105 confined solely to its own compartment.

G indicates a pipe through which gas that has passed through the gas-meter A is conducted to the chamber E, in which is located the valve F.

5 G' indicates a valve by which the flow of gas to the chamber E' can be cut off when desired.

I indicates a pipe communicating with the pipe G between the gas-meter and the valve

10 G', through which pipe I gas is conducted to the sign H, the said pipe I being provided with a small opening in each of the compartments of the same, so that the gas escaping therefrom can be lighted and furnish a very 15 small flame in each compartment, which will serve to light the gas at the burner g', with which each of said compartments is provided, as stated, whenever the gas is allowed to flow through said burner. In Fig. 4 one of such 20 small openings in the pipe I is shown and indicated by g². These small gas-flames that serve to light the burners on the pipe h are appropriately called "pilot-lights." The pipe I is supplied with a valve i for cutting 25 off the gas therethrough when required.

K indicates the pipe through which gas is conducted from the mains or other source of supply to the gas-meter A.

In operation gas will be allowed to flow 30 through the pipe I, the pilot-lights in the several compartments of the sign H will be lighted, and the chamber E' put into communication with the interior of the meter A by opening the valve G' in the pipe G. The 35 escape of gas through the pipe I that feeds the pilot-lights will cause the mechanism of the meter to be set in motion, and through such motion the shaft B' will be turned and cause the valve F in the chamber E' to reverse. Such revolution will successively bring the projections f' over the openings e in the plate B³, thus shutting off the supply of 40 gas to the burners in the various compartments of the sign, and by the passing of the 45 solid portion of the valve over these small openings gas will be again admitted to the pipes h, to be by them conducted to the several compartments of the sign, and by reason of the notching of the rear edge of this solid 50 portion of the valve, as shown, the gas will be admitted to the various pipes successively, and, as will be understood, as each pipe h is brought into communication with the chamber E' the gas emitted from the burner g' of 55 that pipe will be lighted at once by the pilot-light opposite it.

While we have herein referred to the part A as a "gas-meter" and while we deem it best to use an actual gas-meter for operating 60 the rotating valve F, as thereby a single device is used for the operating means and for recording the amount of gas consumed, it is evident, of course, that it is not necessary for the successful operation of our device that

the part A be actually equipped with devices 65 for registering the amount of gas that passes through it. The term "gas-meter" as used herein will therefore be understood to include a device containing mechanism operated by the passage of gas with which our main valve 70 F is connected, whether such part be equipped with registering devices or not.

What we claim as new, and desire to secure by Letters Patent, is—

1. In an intermittent gas-lighting apparatus, the combination with a gas-meter, and pipes for conducting gas thereto and therefrom, of a gas-holding chamber, means for conducting gas thereto from said meter, a plurality of burners, a pipe leading from said gas-holding chamber to each of said burners, a valve in said chamber connected with said meter adapted to admit gas successively to said pipes, and means for moving said valve by the flow of gas through the meter, substantially as specified. 75

2. In an intermittent gas-lighting apparatus, the combination with a gas-meter, and pipes for conducting gas thereto and therefrom, of a gas-holding chamber, means for conducting gas thereto from said meter, a plurality of burners, a pipe leading from said gas-holding chamber to each of said burners, a valve in said chamber connected with said meter adapted to admit gas successively to 90 said pipes, and to successively shut off the supply of gas thereto, and means for moving said valve by the flow of gas through the meter, substantially as specified. 95

3. In an intermittent gas-lighting apparatus, the combination with a gas-meter, and pipes for conducting gas thereto and therefrom, of a gas-holding chamber, means for conducting gas thereto from said meter, a plurality of burners, a pipe leading from said gas-holding chamber to each of said burners, a valve in said chamber connected with said meter adapted to admit gas successively to 100 said pipes, means for moving said valve by the flow of gas through the meter, a pipe connected with said meter and extending to said burners, and a pilot-light burner on said pipe for each burner, substantially as specified. 105

4. In an intermittent gas-lighting apparatus, the combination with a gas-meter and pipes for conducting gas thereto and therefrom, of a gas-holding chamber having a plurality of openings through which gas may escape, a pipe for conducting gas from said meter to said chamber, a rotating valve provided with projections each adapted to be brought, as the valve turns, over one of said openings, and means for rotating said valve by the flow of gas through said meter, substantially as specified. 115 120

5. In an intermittent gas-lighting apparatus, the combination with a gas-meter and pipes for conducting gas thereto and there- 125

from, of a gas-holding chamber having a plurality of openings through which gas may escape, a pipe for conducting gas from said meter to said chamber, a rotating valve having its leading edge provided with a series of projections and its rear edge provided with a series of notches corresponding in size and number to said projections, and means for

rotating said valve by the flow of gas through said meter, substantially as specified.
